ADJUSTABLE SCRAPER BLADE MOUNTING

Harley Rust, Mount Morrison, Colo.

Application April 1, 1949, Serial No. 84,826

3 Claims. (Cl. 37—42)

1

This invention relates to scraper blades of the bulldozer type such as used in leveling or pushing snow, dirt and the like, and in particular a blade mounting for removably attaching a blade to the front of a Jeep or the like wherein the elevation of the blade is readily adjustable and in which the blade is hinged and resiliently held to provide tilting movement when the lower edge of the blade engages a fixed obstruction.

The purpose of this invention is to provide means for removably attaching a scraper blade to the front of a Jeep in which the pitch of the blade is laterally adjustable and also in which the blade is vertically adjustable.

In the usual type of temporary attachments for mounting scraper blades on tractors, Jeeps and the like the blade is bolted in a fixed position to provide rigidity and this does not provide sufficient flexibility for use in scraping snow and the like. With this thought in mind this invention contemplates a mounting for scraper blades wherein the blade is adapted to tilt forward as the lower edge strikes an obstruction and wherein the blade is pivotally mounted for both vertical and horizontal adjustment.

The object of this invention is, therefore, to provide a scraper blade mounting that may be suspended from a bumper or cross beam at the forward end of a Jeep or tractor and braced from the chassis in which the blade is supported from both sides of the chassis and may be adjusted vertically, and also in which the pitch or angle of the blade in relation to the longitudinal center line of the chassis is adjustable.

Another object of the invention is to provide a scraper blade mounting for Jeeps, tractors, and the like in which the lower part of the blade is hinged to a supporting strut and the upper part resiliently held against the strut so that as the lower edge strikes an obstruction the upper part may swing outwardly to prevent damaging the lower part of the scraper.

Another object of the invention is to provide a scraper blade mounting for Jeeps and the like in which the elevation of the scraper may be adjusted by cables from the operator's seat of the Jeep or tractor.

A further object of the invention is to provide an improved mounting for temporarily attaching a scraper blade to a Jeep, tractor, or the like in which the blade is universally adjustable, and in which the mounting is of a comparatively simple and economical construction.

With these and other objects in view the invention embodies a horizontally disposed channel providing a blade holding strut with a blade

2

hinged to the lower edge of the channel and resiliently held against the upper edge with the channel carried by extensible arms pivotally mounted on the lower ends of vertically disposed posts wherein the posts are carried by a bumper or cross beam of a Jeep or tractor with the lower ends supported by struts from the chassis and with adjusting means for raising and lowering the blade carried by the upper ends of the posts.

10 Other features and advantages of the invention will appear from the following description taken in connection with the drawings wherein:

Figure 1 is a side elevational view showing the forward end of a Jeep with the improved scraper blade mounting attached thereto.

Figure 2 is a plan view of the scraper blade mounting with the Jeep omitted.

Figure 3 is a cross section through the scraper blade mounting taken on line 3—3 of Figure 1 20 showing a rear elevation of the blade with the extensible supporting arm shown in section.

Figure 4 is a similar cross section taken on line 4—4 of Figure 1 looking in the opposite direction illustrating the construction of the 25 attachment.

Figure 5 is a longitudinal section through the scraper blade mounting taken on line 5—5 of Figure 2.

Figure 6 is a detail showing a bracket for supporting the rear end of the strut from the chassis and spring hanger of the vehicle taken on line 30 6—6 of Figure 1.

Figure 7 is a detail showing the upper end of the bracket that straddles the side beam of the chassis with the lower part of the bracket broken away.

Referring now to the drawings like reference characters denote corresponding parts, the scraper blade mounting of this invention includes a channel 10 on which a blade 11 is carried, vertically positioned posts 12 and 13 mounted on a bumper 14 and to the lower ends of which the channel 10 is connected by extensible arms having bars 15 and 16 pivotally connected to the channel 10 by pins 17 and 18, respectively, and sections 19 and 20 which are pivotally mounted on a bolt 21 at the lower ends of the posts, and the lower ends of the posts are supported by struts 22 and 23.

50 The blade 11 is pivotally connected to the lower flange 24 of the channel 10 by hinges 25 and the upper part of the blade is resiliently held against the upper flange 26 of the channel by springs 27 and 28 on bolts 29 and 30, respectively, which are positioned with the heads 31 and 32 thereof extended through the blade and

3

with the opposite ends extended through the channel and resiliently held by the springs, the ends of which are positioned against washers 33 and 34 with nuts 35 and 36 holding the washers respectively.

The sections of the extensible arms are provided with spaced openings 37 through which bolts 38 extend and with the outer ends of the arms pivotally connected to the channel 10 the pitch or angle of the channel and blade in relation to the longitudinal center of the Jeep may be adjusted by extending one arm more than the other.

The eye beams forming the posts 12 and 13 are attached to the bumper 14 by the clamps 39 and 40 which are held by a bolt 41 and the lower ends of the posts are supported by the struts 22 and 23 which are attached to plates 42 and 43 carried by the lower ends of the posts, respectively. The plates 42 and 43 also support the bolt 21 on which the rear sections 19 and 20 of the extensible arms are pivotally mounted. The opposite ends of the struts 22 and 23 are freely connected by brackets 44 and 45, respectively, to the side beams 46 of the Jeep with the brackets positioned against the spring hangers 47 as illustrated in Figures 1 and 6. As shown in Figures 6 and 7 the bracket 45 is provided with a flange 48 having a recess 49 therein to receive the lower edge of the beam 46 and a lower end of the bracket is secured by welding, or other suitable means to the strut 23.

An angle 50 is supported from the posts 12 and 13 by angularly disposed braces 51 and 52 on the lower side and 53 and 54 on the upper side which extend upwardly to a cross beam 55 which connects the upper ends of the posts 12 and 13. A gin pole 56, having a hub 57 at the lower end is pivotally mounted on the angle 50 by a pin 58 in ears 59 and 60 and the upper part of the gin pole is connected by chains 61 and 62 to the upper flange 26 of the channel 10, the upper ends of the chains being connected to an eye 63. The upper part of the gin pole is provided with a cross pin 64 that is positioned to be engaged by teeth 65 and 66 of latch bars 67 and 68 which are pivotally mounted on a bracket 69 through a pin 70 in an extension 71 of the bracket. The latch bars may be elevated to release the pin 64 by a shoe 72 on a lever 73 which is pivotally mounted on the bracket 69 by a pin 74 and adapted to be actuated by a cable 75. A cable 76 may also be attached to the upper end of the gin pole 56 whereby the gin pole may be drawn rearwardly to elevate the scraper blade 11 through the supporting channel 10.

With the scraper blade mounted in this manner the elevation of the blade may readily be adjusted and as the lower edge of the blade strikes a fixed obstruction it may move rearwardly against the springs 28 with the upper part tilting forwardly. The pitch or angular position of the blade may also be adjusted through the extensible arms by which the blade is supported from the posts 12 and 13.

The scraper blade mounting may readily be attached to or removed from a Jeep through the bolt 41 by which the clamps 39 and 40 may be adjusted to holding position or removed.

It will be understood that modifications may be made in the parts without departing from the spirit of the invention.

What is claimed is:

1. In a scraper blade mounting, the combination which comprises a pair of spaced vertically positioned posts, means clamping the posts to a

65

70

75

75

cross member of a vehicle, a transversely disposed channel having a vertically disposed web with forwardly extended flanges on the upper and lower edges thereof positioned ahead of the posts, extensible arms pivotally mounted on the posts and attached to the channel, a scraper blade hinged to the flange on the lower edge of the channel, means resiliently holding the upper edge of the scraper blade against the flange on the upper edge of the channel, struts extended rearwardly from the lower ends of the posts to stationary elements on the chassis of the vehicle, a gin pole pivotally mounted on the posts, chains connecting the gin pole to the channel, and latch means retaining the gin pole in adjusted positions with the channel and scraper elevated.

2. In a scraper blade mounting, the combination which comprises a pair of spaced vertically positioned posts, means clamping the posts to a cross member of a vehicle, a transversely disposed channel having a vertically disposed web with forwardly extended flanges on the upper and lower edges thereof positioned ahead of the posts, extensible arms pivotally mounted on the posts and attached to the channel, a scraper blade hinged to the flange on the lower edge of the channel, means resiliently holding the upper edge of the scraper blade against the flange on the upper edge of the channel, struts extended rearwardly from the lower ends of the posts to stationary elements on the chassis of the vehicle, a gin pole pivotally mounted on the posts, chains connecting the gin pole to the channel, latch means retaining the gin pole in adjusted positions with the channel and scraper elevated, and means releasing the said latch means from a remote point.

3. In a scraper blade mounting, the combination which comprises a pair of spaced vertically positioned posts, means clamping the posts to a cross member of a vehicle, a transversely disposed channel having a vertically disposed web with forwardly extended flanges on the upper and lower edges thereof positioned ahead of the posts, extensible arms pivotally mounted on the posts and attached to the channel, a scraper blade hinged to the flange on the lower edge of the channel, means resiliently holding the upper edge of the scraper blade against the flange on the upper edge of the channel, struts extended rearwardly from the lower ends of the posts to stationary elements on the chassis of the vehicle, a gin pole pivotally mounted on the posts, chains connecting the gin pole to the channel, latch means retaining the gin pole in adjusted positions with the channel and scraper elevated, and means releasing the said latch means from a vehicle on which the said scraper blade mounting is carried.
